OPERATING AND CONTROLLING APPARATUS
FOR DRY DOCK SIDE WALLS

Frederic R. Harris, New York, N. Y.

Application August 9, 1944; Serial No. 548,658

7 Claims. (Cl. 114—45)

1

This invention relates to improvements in floating dry docks; especially floating dry docks comprising multiple units, each having transverse wall sections at its two ends; as set forth in my co-pending prior application Serial No. 482,376 for a Multiple unit floating dry dock, filed April 9, 1943, and which on July 10, 1945, matured into Patent No. 2,379,904.

The dry dock described in that application is adapted to be assembled by mooring the pontoon units together side by side, in secure fashion, to make the complete hull of the dock. A dock of this type has walls along each side of the hull; and in the dock of my said prior application, each unit carries two portions or sections of the side walls; said portions or sections being hinged to the decks of the pontoons, so that they can be lowered to the level of the deck when the pontoon is towed or moved about from place to place, and raised upright when the dock is needed for use. In the assembly of the dock, with the pontoons side by side, the various side wall sections at the two ends of each unit come respectively into alignment when they have been elevated; and thus the dock will have a wall extending at full length along each side when the assembling is finished.

In the design of this dock the use of power-operated apparatus to effect the raising and lowering of the wall sections on each unit was taken into account from the beginning, and so was the method of raising and lowering the wall sections by the buoyancy of said sections and the pontoon unit when the latter is partly submerged, as my said prior application discloses. Since the expedient of securing the wall sections to the pontoon by hinged connections, and raising and lowering said sections had never been tried before, no sure indication as to which procedure was preferable existed; and on the best advice and authority the decision was made to rely first on the buoyancy method of raising and lowering the wall sections because a floating dry dock without extra mechanical operating gear for the wall sections appeared to be more desirable for naval service in the present conflict.

After the first dock of this type had been actually constructed, however, thorough tests of the buoyancy method of lifting and lowering the wall sections by partly sinking and then raising the separate pontoons revealed that such a method could be successfully performed in comparatively smooth water, but was slow and tedious at best. In rough weather the buoyancy method becomes difficult and dangerous and even impossible.

Thus, one finally realized that a special power plant should be provided to lift and lower the wall sections; and the space and expense required by such extra equipment are more than offset by the advantages thereof. The wall sections can be more easily and quickly put up and down, and

2

the operation is less subject to local conditions of wind and wave.

Accordingly, it is an object of this invention to provide mechanism which will effect the elevating and lowering of the hinged wall sections of a floating dry dock in a safe and certain manner, which ensures full control of the operation at every step, and which will take up a minimum of space and entail the lowest additional expense.

The invention is fully explained in the ensuing description, taken with the accompanying drawings which present one embodiment of a device capable of serving the intended purpose. I do not, however, wish to be limited to the exact details of structure herein specified, but reserve the right to make changes in the shape, size and arrangement of different parts without deviating from the principle of the invention or its essential character and scope.

On the drawings:

Figure 1 is a side view of a floating dry dock pontoon unit, with hinged wall sections and power connections for same according to this invention; the sections being in elevated position.

Figure 2 is an end view thereof.

Figure 3 is a similar view with the wall section lowered.

Figure 4 is a top view of part of such a unit, with the wall section down.

Figure 5 is a side view of one end of such a unit with the wall section lowered, and

Figure 6 is a similar view of a pontoon unit with the wall section in process of being lifted to fully upright position.

On the drawings the same numerals identify the same parts throughout.

The numeral 1 indicates the hull of a pontoon unit such as I have disclosed in my aforesaid application, with portions of side walls 2 at each end. The hinges 3 for the wall sections are at lower corners along the inner faces of said wall sections. When the wall sections are lowered to horizontal positions, they rest upon blocks or other supports 4 on the deck or floor of the pontoon hull, as indicated in Figure 5.

Adjacent the upper outer corner of each section 2, are two fixed bearing members or blocks 5, secured on the outer face of said section, at an incline, and having a smooth bore through them from top to bottom. In line with each block is a row of triangular braces 6 on the outer face of each wall section; these braces being each shaped like an inverted V. They are inclined and increase in size and height from the top of the wall section down; and each row supports a flat-topped rail 7, which is secured to the braces at the apex of each. The two rails lead from both of the blocks 5 down the outer face of each wall section to a point substantially in the plane of the bottom of said section. The rails and braces are prefer-

ably made of angle bars welded together and to the sections 2 carrying them; or of other suitably shaped parts.

Extending along each rail or track 7 is a heavy shaft 8, one end of which passes through the bore of the block 5, and the other end of which is engaged by a bearing block 9 fixed on the opposite end of the rail 7. The shafts 8 turn freely in the bearings 5 and 9, but cannot move endwise therein. Between the bearings each shaft 8 is threaded over its entire length.

Cooperating with each rail or track 7 is a pair of columns 10. Each column is pivotally connected to a pedestal 11, affixed to the deck of the unit; and the upper ends of these columns are pivotally attached to opposite side faces of a block 12 having a threaded bore which is engaged by the screw 8. This block 12 rests on the flat top of the rail or track 7 and can move along the latter.

On each wall section 2 is a power unit such as an electric motor 13 mounted in a suitable seat on the wall section between the blocks 5 thereon. The rotor thereof is coupled by shafts 14 to the screws 8. Each of these screws has an extremity projecting from the top of the associated blocks and the shafts 14 carry worms 15 that mesh with worm gears 16 on said extremities of the screw shafts 8. The blocks 5 are made fast between brace plates 17, and the screw shaft 8 has collars 18 at the bearings 5 and 9, so that any lengthwise movement of this shaft cannot take place. The collars 18 appear on Figures 5 and 6 but are omitted elsewhere for the sake of convenience and clearness.

In operation, the threaded shaft 8 acts as a capstan screw; and the turning thereof causes the threaded block to slide along the rail 7. When the wall section is prone on the deck, the screw block 12 on the shaft 8 is nearest to the bearing 9, and the jacking columns 10, each pair of which forms a jacking member for one of the wall sections, are inclined towards the wall sections 2. To lift the wall sections, the motor is set into rotation to revolve the screw 8 in such direction that the element 12 is pulled towards the block 5. Tension is thus exerted on the jacking columns and the section 2 is pulled towards upright position. When the section is fully raised, the jacking columns are vertical. In the final stage of the raising, the wall sections settle of their own weight with their lower ends on the deck of the hull 1, and the screws 8, columns 10 and associated parts are rugged enough to steady the sections and resist compression and all other stresses at this time.

To lower the wall sections, all fixed connections between them and the dock floor are removed. The motor then is reversed and rotates the screws 8 in the opposite direction to push the blocks 12 towards the bearings 9.

The power apparatus for raising and lowering the wall sections is therefore simple and easy to install and operate quite efficient and certain in action and capable of giving the desired result in the shortest possible time.

Having described my invention, what I believe to be new is:

1. A dry dock having a pontoon hull, a wall section hinged thereon, a pair of columns pivotally mounted on said hull and joined together at their upper ends, a capstan screw on one face of said wall section, and an element connecting

the screw to the upper ends of both columns, and means for rotating said screw to actuate said columns to raise and lower said wall section to vertical and horizontal position respectively.

5 2. A dry dock having a pontoon hull, a wall section hinged thereon, a capstan screw on said wall section, a motor on said wall section to rotate said screw, and members connected to the hull and an element connecting said members to said screw to raise and lower said wall section to vertical and horizontal position respectively.

10 3. A dry dock having a pontoon hull, a wall section hinged thereon, a capstan screw on one face of said wall section, means for mounting said screw in inclined position with respect to said face, a motor on the top of said wall section, gearing coupling the motor to said screw, and one or more members connected to the hull and an element attached to said members and engaged by said screw.

15 4. A dry dock having a pontoon hull, a wall section hinged thereon, a capstan screw on said wall section, a motor on said wall section, gearing connecting said screw to the motor, a threaded block on said screw, and means adjacent the outer face of the section connecting the block to the hull.

20 5. A dry dock having a pontoon hull with a deck, a wall section hinged to the deck, a capstan screw on one face of the wall section, a motor on the wall section, gearing connecting the motor to the screw, a threaded block engaged by the screw, an inclined track for the block on the wall, and means comprising members pivotally attached to the block and to the deck to raise or lower the wall section when the screw is rotated.

25 6. A dry dock having a pontoon hull with a deck, a wall section hinged thereon, a capstan screw on one face of the wall section, a motor on said wall section, gearing connecting the motor to the screw, a threaded block on the screw, a track on the wall and inclined to one face thereof for said block, a pair of columns pivotally connected to the block at one end, and pedestals affixed to the deck and pivotally connected to said columns at their opposite ends.

30 7. A dry dock having a pontoon hull, a wall section hinged thereon, a capstan screw attached to the outer face of the wall section, a column pivotally mounted on said hull adjacent the outer face of the wall section, an element connecting the screw to the column and means for rotating the screw to actuate the column to raise and lower said wall section to upright or horizontal position.
